CLAIM

We claim the ornamental design for a toothbrush handle, as shown and described.

DESCRIPTION

FIG. 1 is a front isometric view of a toothbrush handle with a toothbrush head shown for environment.

FIG. 2 is a front isometric view of the toothbrush handle of FIG. 1.

FIG. 3 is a front elevation view of the toothbrush handle of FIG. 2.

FIG. 4 is a rear elevation view of the toothbrush handle of FIG. 2.

FIG. 5 is a right side elevation view of the toothbrush handle of FIG. 2.

FIG. 6 is a left side elevation view of the toothbrush handle of FIG. 2.

FIG. 7 is a top plan view of the toothbrush handle of FIG. 2; and,

FIG. 8 is a bottom plan view of the toothbrush handle of FIG. 2.

The broken line showing of the toothbrush head in FIG. 1 depicts environmental structure and forms no part of the claimed design. All other broken lines depict portions of the toothbrush handle that form no part of the claimed design.

1 Claim, 4 Drawing Sheets

Related U.S. Application Data

a division of application No. 29/587,868, filed on Dec. 15, 2016, now Pat. No. Des. 845,636.
